UNITED STATES PATENT OFFICE.

GEORGE RUPLEY, OF DULUTH, MINNESOTA, ASSIGNOR TO THE VENDING MACHINE COMPANY, OF DULUTH, MINNESOTA.

VENDING-MACHINE.

SPECIFICATION forming part of Letters Patent No. 737,665, dated September 1, 1903.

Application filed July 12, 1902. Serial No. 115,344. (No model.)

To all whom it may concern:

Be it known that I, GEORGE RUPLEY, a resident of Duluth, in the county of St. Louis and State of Minnesota, have invented certain new and useful Improvements in Vending-Machines; and I do hereby declare the following to be a full, clear, and exact description of the invention, such as will enable others skilled in the art to which it appertains to make and use the same.

My invention relates to an improved vending-machine, the object of the invention being to provide improved mechanism for ejecting the articles or receptacles containing the same and insure the operation of but a single receptacle at a time, and, further, to provide improved means for retaining all of the receptacles in position and releasing but a single one at a time.

With these objects in view the invention consists in certain novel features of construction and combinations and arrangements of parts, as will be more fully hereinafter described, and pointed out in the claims.

In the accompanying drawings, Figure 1 is a view, partly in section, illustrating my improvements. Fig. 2 is a sectional view showing some of the trays released. Fig. 3 is a sectional view taken at right angles to Fig. 2, and Figs. 4, 5, and 6 are views of various details of construction.

1 represents the frame of the machine, in which is mounted a shaft 2, turned by a crank-arm or by any approved mechanism, and, if desired, coin operated or controlled mechanism may be provided to lock this shaft against turning. Secured to the rear of the frame and supporting one end of a series of trays or receptacles are vertical rods 3, which latter are bent or made with shoulders 4 to support the trays, which are slotted, as shown at 5, to move on the rods. These trays are supported at their opposite end on toothed wheels 6, secured on shaft 2, and the teeth of said wheels are made with one curved face tapering to the base of the other tooth for a purpose which will hereinafter appear. These trays are adapted to contain the articles to be vended, and the purpose of my invention is to provide positive means for ejecting or tilting the bottom tray to eject the article or ar-

ticles thereon. To prevent the movement of the trays until the proper time and then only permit a single tray to be moved, I mount a hinged frame 6^a as shown in detail in Fig. 5 55 and secure to shaft 2 a cam-wheel 7 to operate the same. This frame comprises a long arm 8, bent at right angles to project beneath the trays and made with an upturned finger 9 to project into an opening in the bottom tray and prevent its movement. The frame 6^a is also made with an upright arm 10, bent at an angle at its upper end and resting on the periphery of cam-wheel 7 and adapted to be moved thereby to move locking-arm into 65 position to lock the trays or permit said arm to fall when a tray is to be ejected. This cam-wheel 7 comprises, in effect, four teeth, one face of the teeth tapering or inclining to the base of the adjacent tooth and forming a 70 cam-face to engage the bent end of arm 10 and lift the finger 9 into the opening in the tray and hold it there until a tooth of the cam-wheel is passed, when the arm 10 will fall onto the lowest point of the next cam-face and the tray be freed long enough to permit its ejection. All of the trays except the bottom one are prevented from longitudinal movement by a hinged bar 11, adjacent to the ends of the trays. This bar may be swung 80 back out of the way when the trays are returned to their horizontal operative position. 75

Instead of employing frame 6^a I might secure to the bar 11 a spring-pressed finger 12 to yieldingly hold the bottom tray and prevent its accidental movement; but the frame 6^a is preferred.

The operation of my improvement is as follows: When it is desired to remove an article, the shaft 2 is turned to turn wheels 6 and 90 7, the latter turning far enough to permit arm 10 to fall from one tooth of the wheel onto the other, thus dropping arm 8 to release finger 9 from the opening in the bottom tray. The turning of wheels 6 serves to move a 95 tooth of said wheels against the end of the lowest tray and force the latter longitudinally far enough to align the slots 5 therein with shoulders 4, when the tray will fall to a vertical position shown and eject the article or articles thereon. The next cam-face of wheel 7 immediately begins its action on bent arm

10 to elevate arm 8 and raise the finger 9 into the opening of the next tray and hold the same against movement until the operation above described is repeated, and by repeating 5 this operation again and again all of the trays can be emptied in their order from the lowest to the highest.

A great many slight changes might be made in the general form and arrangement of the 10 several parts described without departing from my invention, and hence I do not limit myself to the precise construction set forth, but consider myself at liberty to make such slight changes and alterations as fairly fall 15 within the spirit and scope of my invention.

Having fully described my invention, what I claim as new, and desire to secure by Letters Patent, is—

1. The combination with a tray or article 20 to be moved, of a rod having a shoulder to support one end of said tray or article, and a toothed wheel to engage the tray and move it from said shoulder.

2. The combination with a series of trays 25 or articles disposed one on top of the other, of a rod having a shoulder to support one end of said trays or articles, which latter are slotted to receive the rod, and a toothed wheel to engage the bottom tray or article and move 30 it to aline its slot with the shoulder and permit the tray or article to fall.

3. The combination with a series of trays 35 or articles to be removed disposed one on top of the other, of a rod having a shoulder to support one end of the trays or articles which

latter are slotted to receive the rod, a toothed wheel to engage the bottom tray or article and move it to aline its slot with the shoulder and permit the tray or article to fall, and locking means to engage the next lowest tray and 40 hold it in place until the wheel is again operated.

4. The combination with a series of trays or articles to be removed disposed one on top of the other, of a shaft, a toothed wheel on 45 said shaft supporting one end of the trays and adapted to eject said bottom tray when the shaft is turned, mechanism to lock said tray and a cam-wheel on the shaft to release said locking mechanism.

5. In a vending-machine, the combination with a series or pile of trays, of a shaft, toothed wheels on said shaft supporting one end of the trays and adapted to eject the lowest tray when the shaft is turned, a hinged 55 frame, an arm on said frame having a finger to project into an opening in the lowest tray and lock it against movement, a cam-wheel on the shaft, and a bent arm on the frame engaged by the cam-wheel to hold said finger in 60 the opening and permit the frame to fall and release the tray when the shaft is first turned.

In testimony whereof I have signed this specification in the presence of two subscribing witnesses.

GEORGE RUPLEY.
